JAMES A. BLAIR, OF SPOKANE, WASHINGTON, ASSIGNOR OF FORTY-NINE ONE-HUNDREDTHS TO WILLARD E. BARNHART, OF SPOKANE, WASHINGTON.

TRAIN-ORDER-DELIVERING APPARATUS.

1,252,389.

Specification of Letters Patent.

Patented Jan. 8, 1918.

Application filed May 28, 1917. Serial No. 171,517.

To all whom it may concern:

Be it known that I, JAMES A. BLAIR, a subject of the King of Great Britain, residing at Spokane, in the county of Spokane 5 and State of Washington, have invented certain new and useful Improvements in Train-Order-Delivering Apparatus, of which the following is a specification.

My invention relates to improvements in train order delivering apparatus, and more particularly to mechanical means comprising a station or train despatcher's apparatus set along the track, and a cab and caboose carried contrivance, both adapted to coöperate 15 to effect delivery of train orders to the engineer and conductor of a passing train while in motion.

The object of the invention resides in the provision of a device of the foregoing character embodying novel features of construction, comprising a minimum of parts with consequent cheapness and simplicity, and adapted to perform the above functions in an efficient, positive, and thoroughly reliable 25 manner under all conditions.

In a practical embodiment of the invention as illustrated in the accompanying drawings—

Figure 1 indicates the relative positions 30 of a despatcher's device and the coöperating device as carried by the engine cab of a passing train, the support of the despatcher's device being shown fragmentally and partly in section and the order holding arms in both 35 operative and inoperative positions, and the train contrivance arms which are adapted to catch the orders being shown in both operative and inoperative positions, all to be hereinafter more fully explained.

Fig. 2 is a view from above of a station 40 and train device, the former having the support indicated sectionally while the cab is indicated fragmentally and diagrammatically.

Referring more specifically to the drawings, and first describing the station apparatus, the numeral 1 designates an upright, hollow or tubular support which is shown of rectangular design in cross-section and is of 45 a height adapted to maintain the order holding arms 2 in proper relative positions with respect to the catching arms of the train when set horizontally or for operation. Each one of the three upper arms 2 is pivotally mounted on a bolt 3 which extends 55

transversely of the support and has its ends secured in opposite side walls thereof and in close parallel relation to the front wall or that wall facing the train. Each rod like arm extends through a slot or aperture in 60 said front wall and is bent to encircle its respective bolt in a convolute bend 4 to provide a bearing on the bolt, while an extended end 5 within the support is curved upwardly or in a U-bend and provided with an eye to 65 which is attached a counterweight 6 which is adapted to throw the arms upwardly out of operative positions when the same are released as hereinafter described.

The uppermost arm 2 is provided at its 70 outer end with a pivotally mounted finger 7 one end of which extends outwardly from the end of the arm its remaining end being connected to the arm by means of a coil spring 8 which is adapted to retain the finger 75 in normal alined relation to the arm. The two intermediate arms 2 are each provided at their outer ends with a pair of fingers 7 and springs 8 similar to that of the uppermost arm.

The bottom arm 2 is pivotally supported upon the front face of the station standard 1 by means of an eye 9 the arm being bent at right angles to provide an abutment 10 which engages the face of the standard to 85 limit upward movement of the arm. Similar right-angular bends or offsets 11 in the three upper arms 2 serve to limit downward movement of the same when set for operation.

Describing the train carried apparatus 90 which is adapted to coöperate with the station device just referred to, the same is intended to comprise a catcher arm for the engine cab and a catcher arm for the caboose, while where two engines are employed to 95 a train a separate catcher arm is provided for the cab of each. The station apparatus illustrated is adapted to accommodate either a double or single header.

The catcher arm 12 shown in operative 100 position in solid lines is similar in every respect to the corresponding equipment for a caboose or for either of two engines, but occupies the position intended for use where a single engine is doing the hauling or that 105 of the second engine of a double-header. The catcher arm is pivotally mounted near its inner end upon a bracket 13 secured to the outer face of the engine cab or caboose and as indicated at 14, the portion of the 110

arm 15 between said pivotal point and the inner extremity of the arm being adapted to be received and retained in a slotted housing 16 in the wall of the cab or caboose when 5 the arm is extended for operation. The outer portion 17 of the arm supports a coil spring 18 in parallel relation thereto.

The uppermost catcher arm which is shown in inoperative position and held against 10 the face of the cab by spring clips 19 is the arm intended for use in connection with the leader engine of a double header, while the bottom catcher arm indicated in dash-lines and in catching position is that arm intended for the caboose. All three arms when not in use are adapted to drop down in parallel relation with the side of the vehicle and to be secured in place by the spring clips 19.

20 In delivering one or a series of orders to a passing train a cord 20 having loops 21 at both of its ends is attached in a vertical and taut position to the fingers 7 and between adjacent arms, a separate cord being 25 used for each order of a series, the orders, indicated by the numeral 22 being held by clips 23 carried by the cords. The catcher arm is intended to catch a particular despatch held by the station apparatus is positioned relative to such apparatus on a plane 30 intermediate of the respective order delivering arms and the coil spring 18 thereof is adapted to engage the taut cord and grip the same in passing, the cord being released 35 from the fingers 7 upon pivotal movement thereof caused by the impact. When the station arms are released after the catching operation the counter-weights will position the same vertically, while in the case of the 40 bottom station arm such release will allow the same to drop down out of the way.

Having described the invention, I claim:—

1. In a device of the character described, a station apparatus and a train carried apparatus adapted to coöperate to effect delivery of despatches to the train, said station apparatus consisting of an upright support, a plurality of despatch holding arms pivotally mounted thereon in superposed relation, a finger pivotally mounted on the outer end of each arm and extending beyond the extremity thereof, a despatch holding cord adapted to be supported in vertical position by the fingers of two adjacent superposed arms; said train carried apparatus consisting of a pivotally supported and vertically swinging catcher arm, a coil spring carried by said catcher arm in parallel relation thereto and adapted to engage and grip the

despatch holding cord of the station ap- 60 paratus.

2. In a device of the character described, a station apparatus and a train carried apparatus adapted to coöperate to effect delivery of despatches to the train, said station apparatus consisting of an upright support, a plurality of despatch holding arms pivotally mounted thereon and adapted to swing vertically, said arms being in superposed relation, an inner end extension of each arm, a counterweight carried by the inner end extension, a finger pivotally mounted on the outer end of each arm and extending beyond the extremity thereof, a spring connecting the arm and finger and adapted to retain the finger in normal parallel relation to the arm, a despatch holding cord adapted to be supported in vertical position by the fingers of two adjacent superposed arms; said train carried apparatus consisting of a vertically swinging catcher arm pivotally supported near one end, a coil spring carried by said catcher arm at its outer end portion and in parallel relation thereto and adapted to engage and grip the despatch cord of the station apparatus.

3. In a device of the character described, a station apparatus and a train carried apparatus adapted to coöperate to effect delivery of despatches to the train, said station apparatus consisting of an upright support, a plurality of despatch holding arms pivotally supported thereby, each arm having a convolute bend near its inner end encircling a bolt, a right angular offset adapted to abut the face of the support and limit downward movement of the arm, and an inner end extension, a counterweight carried by the inner end extension, a finger pivotally mounted on the outer end of each arm and extending beyond the extremity thereof, a spring connecting the arm and finger and adapted to retain the finger in normal parallel relation to the arm, a despatch holding cord adapted to be supported in vertical position by the fingers of two adjacent superposed arms; said train carried apparatus consisting of a vertically swinging catcher arm pivotally supported near one end, a coil spring carried by said catcher arm at its outer end portion and in parallel relation thereto and adapted to engage and grip the despatch cord of the station apparatus.

In testimony whereof I hereunto affix my signature.

JAMES A. BLAIR.
